UNITED STATES PATENT OFFICE.

CHARLES G. ASHLEY, OF TORONTO, ONTARIO, CANADA, ASSIGNOR TO GENERAL ENGINEERING AND CONSTRUCTION COMPANY, LIMITED, OF TORONTO, ONTARIO, CANADA, A CORPORATION OF ONTARIO, CANADA.

DUPLEX PRINTING-TELEGRAPH SYSTEM.

1,301,213.

Specification of Letters Patent. Patented Apr. 22, 1919.

Application filed May 7, 1917. Serial No. 166,802.

To all whom it may concern:

Be it known that I, CHARLES G. ASHLEY, a citizen of the United States of America, and a resident of the city of Toronto, county 5 of York, and Province of Ontario, Canada, have invented a new and useful Improvement in Duplex Printing-Telegraph Systems, of which the following is a specification.

- 10 My invention relates to rapid printing telegraph systems of the class in which the characters necessary for the transmission of intelligence are built up of impressions, in proper relation and sequence, from a comparatively small number of types representing the various component parts of the letters or numerals to be formed, and pertains specifically to duplex arrangements of such systems.
- 20 The object of my invention in general comprises an improvement on my Patent No. 1,193,217, August 1st, 1916, specifically my object is to provide a duplex printing telegraph system which shall embody all the features necessary for high speed transmission and infallibility of operation through freedom from earth current disturbances, each of maintaining the line balance and simplicity of apparatus and operation.
- 25 These and other desirable features which will hereinafter be pointed out and described I accomplish by a novel system of circuits and apparatus wherein the line conductors are uninterruptedly connected with the earth at their extremities while the transmitting and receiving devices are merely inductively linked to the line.

In the drawing which accompanies and forms a part of this specification I have 40 illustrated diagrammatically the apparatus and circuits of one embodiment of my idea.

Referring to the drawings, which as usual represent one end of a duplex, comprising both a transmitting and receiving station, 45 the transmitter comprises a source of alternating current which may be as indicated a magneto generator with a permanent field 2, armature 3 and slip rings 4 and 5 carried on a shaft 8. The shaft 8 carries a pinion 11 50 which meshes with spur gear 10 carried on a shaft 9, which carries also rigidly attached thereto a sprocket wheel 12. The perforated transmitting tape, used with systems of this

type, is engaged by the teeth of the sprocket wheel and the tape is thus drawn between 55 the platen 13 and the brushes 14 and 15 in step with the alternations of the alternating current generated in the armature 3. Such transmitting mechanism is illustrated and described in my Patent No. 1,095,541, May 60 5th, 1914, and is believed to be sufficiently old in the art to require no detailed description. It is usual, however, with such transmitting mechanism to connect one slip ring to earth, the other ring to the platen, and the brushes 65 with the line conductors, and thus the connection of the line with earth is rapidly interrupted by the passage under the brushes of a perforated tape. In contradistinction to such systems I connect brush 7 to platen 13, 70 brush 6 through conductor 16 with the corresponding terminals of the primaries of two transformers 19 and 20, the remaining terminals of these transformers are connected to brushes 14 and 15 respectively. One 75 terminal of the secondary of transformer 19 is connected to earth while the remaining terminal is connected through conductor 21 with the conductor joining the coils 29 and 30 of the retardation coil 23, the remaining 80 terminal of coil 29 is connected to line conductor 25 while the remaining terminal of coil 30 is connected to earth through an artificial line 27. Similarly one terminal of the secondary of transformer 20 is connected to 85 earth and the remaining terminal is connected to line conductor 26 and to the artificial line 28 through the balanced coils 31 and 32 of the retardation coil 24. Thus the extremities of the line conductors 25 and 26 are 90 always permanently and uninterruptedly connected to earth because the perforated transmitting tape in passing between the platen 13 and the brushes 14 and 15 merely 95 opens and closes the primary or local circuit of the transformers 19 and 20 to send through the action of the transformers 19 and 20 the selected impulses over the line conductors 25 and 26.

In order to scavenge the line conductors 100 from static effects and to prevent tailings, brush 7 of the generator is connected through resistances 17 and 18 with the transmitter brushes 14 and 15, that through the action of the transformers 19 and 20 an uninterrupted alternating current of low intensity 105

- in phase with the transmitting impulses may be placed on the line at all times. The action of the transmitting tape therefore is to allow, when impulse perforations therein 5 pass under the contact line of brushes 14 and 15 with the platen 13, selected half waves of the scavenging or curb current to be augmented through short circuiting the curb resistances 17 and 18.
- 10 The transmitting mechanism as will now be seen comprises merely a means for placing selectively upon the line conductors selected half waves of alternately current of predetermined polarity and in predetermined 15 sequence.
- 15 The receiving apparatus comprises four polarized relays 43, 63, 73 and 83. The windings 47, 48 and 67, 68 of one pair of these polarized relays are connected in series 20 and to the terminals of a coil 33 wound on the core of the retardation coil 23. Similarly the windings of polarized relays 73 and 83 are connected in series and to a coil 34 carried on the core of retardation coil 24.
- 25 As indicated on the extremities of the permanent magnets polarizing the polarized relays, the relays of each pair are oppositely polarized so that they may be selectively operated by the polarity of the impulses generated in the coils 33 and 34 by the passage 30 of current from the line wires through the coils 29 and 30, and 31 and 32 in series. Current impulses from the home or local transmitting device divide equally, owing 35 to the artificial lines 27 and 28, and pass through the coils 29 and 30, and 31 and 32 on the retardation coils in opposite directions, the action being the same as in a differential duplex, with the result that no current 40 is induced in the coils 33 and 34 and the polarized relays connected to these coils are therefore not affected or operated by impulses from the home transmitter.
- 45 The armatures 44, 66, 77 and 88 of the polarized relays 43, 63, 73 and 83 respectively are all connected to one terminal of condensers 42, 62, 72 and 82 respectively, the remaining terminals of these condensers are connected through a common return conductor 35 with one terminal, say the negative, of a source of direct current. The armatures of the polarized relays are all biased to rest against corresponding relay contacts 45, 65, 75 and 85, and these corresponding relay contacts are connected through ballast resistances 41, 61, 71 and 81 respectively with the common return conductor 35. The open contacts 49, 69, 79 and 89 of the coils are connected by conductors 50, 91, 92 and 93 respectively with one terminal of the operating magnets of the receiver printer 50, 60, 70 and 80 respectively, the remaining terminals of these receiver printer coils are all joined to a common 55 return conductor 36 which is connected to the positive terminal of the direct current source. The receiver printer is essentially the same as that described in my Patent 1,193,217, August 1st, 1916, and comprises four printing members as 52, 53, 54 and 55, each bearing a type as 52¹, 53¹, 54¹ and 55¹ which is adapted to print an impression of a letter or numeral component. These type bearing members are pivoted in a support 59 by means of a pin 51. A strip of impression 75 paper or typewriter ribbon 57 is maintained above a strip of receiving tape 56, which by suitable mechanism, is drawn between the type members and an anvil 58 and is maintained thereby adjacent to the type faces in order to receive impressions therefrom. The building up of the letters or numerals in this type of receiver printer is in all respects similar to that described in my patent hereinbefore referred to. However, as the selection of the type to be printed is in my present system controlled by polarized relays as 43 it is obvious that the receiver printer magnets need not be polarized as shown in my former patent hereinbefore referred to, it being only necessary in using this type of receiver printer with my present system to restrain the types from contact from the paper by means of spring tension. 85
- 90 As hereinbefore explained current impulses from the home transmitter do not influence the local or home receiver, while impulses from the distant transmitter traverse the line conductors 25 and 26 and cause the operation of the local receiver apparatus as follows:
- 95 Incoming current impulses on line 25 traverse coil of retardation coil 23 then the current impulse divides and part of the current is led through conductor 21 through the secondary of transformer 19 to earth, while the other portion of the current is led through coil 30 and artificial line 27 to earth. As the incoming current impulse traverses coils 29 and 30 of retardation coil 23 in series, and in the same direction, current is induced in coil 23. This induced impulse traverses the windings of the relays 43 and 63 and dependent upon the polarity of this induced impulse the armature of either relay 100 43 or 63 is moved to break contact with its contact of rest and make contact with its normally open contact, and the armature of the remaining relay of the pair is held more tightly in its normal position. We will assume that the polarity of the impulse in question is such as to operate armature 44 to break contact with contact 45 and make contact with contact 49 thus a circuit is normally formed from the negative terminal 105 of the direct current source through conductor 35, condenser 42, armature 44, contact 49, conductor 90, receiver printer coil 50 and through conductor 36 with the positive side of the direct current source. The 110
- 115 65
- 120 70
- 125 75
- 130 80

condenser 42 is thus momentarily connected, in series with the receiver printer coil 50, to the source of direct current and therefore a rush of current takes place through the coil 50 to charge the condenser 42 to the potential of the direct current source which results in operating the printing member 52 to record its type face 52¹. The armature 44 after, as has been stated, momentarily making contact with contact 49 falls back to its normal position of rest in contact with contact 45, and the condenser 42 is therefore discharged through the resistance 41. Similarly a current impulse of the opposite polarity over line 25 induces a current impulse in coil 33 which results in operating relay 63 to print member 53¹. Likewise impulses of predetermined polarity operate relays 73 and 83 to cause their associated receiving 10 printing magnets 70 and 80 respectively to operate their associated printing members 54 and 55 to record type faces 54¹ and 55¹. Thus through the proper selection of impulses, letters and numerals may be recorded 15 upon the receiving tape 56 as explained in my patent hereinbefore referred to.

It is apparent from the foregoing that my improved duplex printing telegraph system is extremely simple, that as the extremities 20 of the duplexed lines are through the transmitting transformers and artificial lines always permanently grounded that a balance once obtained is not interrupted or destroyed by the passage of the perforated 25 tape through the transmitting mechanism. Further, as the receiving devices are not physically connected to the line but are inductively linked thereto it is obvious that disturbances caused by earth currents are 30 reduced to a minimum.

While I have illustrated and described but one embodiment of my device it is to be clearly understood that I am not limited thereto but may make numerous changes in 35 the details thereof without departing from the spirit or narrowing the scope of my invention.

Having thus described my invention what

I claim as new and desire to secure by United States Letters Patent is as follows:

50

1. In a printing telegraph duplex, a pair of transformers, line conductors connected to earth through the secondaries of said transformers, transmitting apparatus connected to the primary of said transformers, 55 a pair of retardation coils, balancing means for said line conductors, and receiving apparatus inductively linked to said line conductors through said retardation coils.

2. In a printing telegraph duplex, a pair 60 of transformers, balanced line conductors connected to earth through the secondaries of said transformers, transmitting apparatus connected to the primary of said transformers, a pair of retardation coils connected to said line conductors, a plurality of polarized relays inductively linked to said line conductors through said retardation coils, and a receiver printer operated by 65 said polarized relays.

3. In a printing telegraph duplex, a pair 70 of balanced line conductors, a plurality of transformers connected to said line conductors, transmitting apparatus connected to said line conductors through certain of 75 said transformers, a plurality of polarized relays inductively linked to said line conductors through certain other of said transformers, and a receiver printer operated by 80 said relays.

4. In a printing telegraph duplex, a transformer, a line conductor connected to earth through the secondary of said transformer, transmitting apparatus connected to the primary of said transformer, a retardation 85 coil, balancing means for said line conductor and receiving apparatus inductively linked to said line conductor through said retardation coil.

Signed by me at Toronto, county of York 90 and Province of Ontario, this 2nd day of May, 1917.

CHARLES G. ASHLEY.
